UNITED STATES PATENT OFFICE.

FRED H. HAYWOOD, OF CLEVELAND, OHIO.

BARREL AGITATOR.

Application filed March 7, 1925, Serial No. 13,800. Renewed October 17, 1927.

This invention relates to improvements in barrel agitators and has for its object the provision of a simple and efficient device adapted to be permanently installed in barrels or removable and insertible at will. The invention is especially adapted for paint barrels and is so designed that it may be readily placed in filled or empty barrels, and as readily withdrawn, even though the solid 5 matters or pigments, contained in the paint, may have settled to the bottom of the barrel and formed therein a more or less solid cake.

A further object of the invention is to provide an agitator that will be adapted to 10 scrape the bottom of a barrel and thoroughly mix the contents.

Other objects of the invention and the features of novelty will be apparent from the following description taken in connection 15 with the accompanying drawings, of which—

Fig. 1 is a vertical section of a barrel having my invention applied thereto;

Fig. 2 is a perspective view of the main 20 elements of the agitator shown in Fig. 1; and

Fig. 3 is a bottom plan of the parts shown 25 in Fig. 2 with one part shown in section.

In the drawings, 1 indicates a container or 30 barrel, of circular cross section, and 2 an opening or bung-hole in the top head of the barrel, at the center thereof. Affixed to the top head of the barrel, and surrounding the opening 2, is a sleeve 3 having a flange 4 which is suitably affixed to the barrel head. The sleeve 4 is exteriorly threaded, as indicated at 5, and a cap 6 is adapted to screw 35 over the sleeve and form a closure for the bung-hole.

The agitating means or stirrer, forming 40 the subject matter of my invention, includes a rod 7 which is welded or otherwise secured to the inner side of the bottom head, at the center, as indicated at 8, and this rod extends axially of the barrel to a point adjacent to or through the opening 2 but should not be 45 so long that it would interfere with the tightening of the cap 6. The upper end of the rod 7 is preferably free, as shown. A link or scraper blade 9 is normally arranged at the bottom of the barrel and, intermediate 50 its ends, is provided with a quarter twist and at its inner end with a slot 11 through which the rod 7 is adapted to be freely passed. The inner end of the blade 9 is upturned, indicated at 12, to permit the blade to be 55 readily passed through the sleeve 3, when in engagement with the upper end of the rod 7.

Pivottally connected to the outer end of the blade 9, as at 13, is an upright blade 14 which, intermediate its ends, is provided with a bend 15 to permit the upper end of this blade to project into or through the sleeve 3, as shown in Fig. 1. The blade 14 is also provided with a quarter twist 16 so that its lower end may be conveniently pivoted to the outer end of the blade 9, as shown. The upper end 17, of the blade 14, is provided with an opening 18 to receive a rod or other form of tool by which the stirrer may be rotated about the rod 7.

The operation of the stirrer will now be 70 briefly described. As already indicated, the rod 7 will be permanently attached to the barrel and extend to a point adjacent to or through the opening 2 in the top head. When it is desired to place the agitator in 75 the barrel, the operation is the same whether the barrel is filled or empty. The upper end of the rod 7 preferably extends above the contents of the barrel so as to be visible through the sleeve 3. The blade 9 is passed 80 endwise through the sleeve 3, and the rod 7 is entered into the opening 11. The blade 14 is held above the barrel with the blade 9 hanging therefrom and the two blades are then lowered into the barrel. The blade 14 85 follows the blade 9 endwise into the barrel, as will be readily understood, and, if there is an accumulation of solid matter or pigment in the bottom of the barrel it will usually be in the form of a cake several 90 inches thick and when the end 12 of the blade 9 reaches this cake the blades 9 and 14 are rotated about the rod 7, by means of a rod 95 or wrench attached to the blade 14, as previously described. The blade 9 will thus be caused to bore its way through this cake of solid material and, by passing downward on the blade 14, the blade 9 will make a gradually enlarging conical hole in the cake until the blade 9 reaches the horizontal position 100 shown in Fig. 1. Rotation of the device may then be continued until the contents of the barrel are thoroughly stirred.

In case the stirrer or agitator is permanently installed in the barrel and shipped therewith, the accumulation of solid matter or pigment is likely to so embed the blade 9 and the lower end of the blade 14 as to make it very difficult, if not impossible, to rotate the stirrer, in the arrangement shown in Fig. 1. Under these conditions the blade 14 110 is partially withdrawn so as to raise the blade

9 to a substantially vertical position. The stirrer may then be rotated and the blade 9 will gradually bore through the cake of solid material until the parts again reach the position shown in Fig. 1.

The arrangement of the blade 9 on the bottom of the barrel, and the lower end of the blade 14 adjacent the side of the barrel, insures the thorough mixing of all of the contents. The arrangement of the threads 5 on the outside of the sleeve 3 prevents mutilation of the threads by engagement of the blade 14 with the sleeve, when being rotated.

Having thus described my invention, what I claim is:

1. In combination with a barrel having an opening, a rod secured within the barrel and extending from a point opposite the opening to said opening, a blade turnably mounted on said rod, a second blade pivotally attached to the free end of the first-mentioned blade and extending upwardly toward the top of the rod.

2. In combination with a barrel having a central opening at one end, a rod extending from the bottom of the barrel up to and through said opening, a blade pivotally and slidably mounted on the rod adjacent the bottom of the barrel, and a second blade pivotally secured to the free end of the first-mentioned blade and extending upwardly through the opening in the barrel.

3. In combination with a barrel having a central opening in one end thereof, a rod within the barrel extending axially thereof up to said opening, a blade having a slot in one end of a size to permit the rod to be passed therethrough, said blade being adapted to be passed through said opening, and a member hingedly connected to the free end of the blade and extending upwardly through said opening.

4. In a device for agitating the contents of barrels, the combination of two members hingedly joined together, one of said members being shorter than the other, the shorter member having means at one end to permit the passage of the rod therethrough, the longer member being reversely bent intermediate its ends.

5. In combination, a barrel having a central opening in one of its ends, a rod anchored to the other end of the barrel and extending axially of the same to a point adjacent said opening, means adapted to be swung around said rod as an axis including two stirring elements hingedly connected at one of their ends, one of said elements being turnably mounted on said rod, the other

of said elements extending upwardly adjacent the barrel wall and being bent intermediate its ends and directed upwardly through said opening.

6. In combination with a barrel having an opening at one end, a device for agitating the contents of the barrel including a rod anchored to the other end of the barrel and extending axially thereof to a point adjacent said opening, a pair of link members one of which is turnably mounted at its end on the rod and the other of which extends up and through said opening, both of said members adapted to be removed from the barrel by being drawn through said opening thereof.

7. In combination with a barrel, a rod secured to the inner side of one end of the barrel and projecting to a point adjacent the other end of the barrel, said other end of the barrel having an opening in alignment with said rod, and a stirrer insertible through said opening and having one end pivoted on said rod, the opposite end of said stirrer projecting through said opening.

8. In combination with a barrel, a rod secured to the inner side of one end of the barrel and projecting to a point adjacent the other end of the barrel, said other end of the barrel having an opening in alignment with said rod, and a stirrer comprising a plurality of pivotally connected members insertible through said opening, one of said members being pivotally arranged on said rod and another of said members projecting through said opening.

9. In combination with a barrel, a pivot member secured to the inner side of one end of the barrel, the other end of the barrel having an opening, and a stirrer comprising a bar pivotally connected with said member and normally extending parallel with the first mentioned end of the barrel, and a bar pivoted to the outer end of the first mentioned bar and extending longitudinally of the barrel to said opening.

10. In combination with a barrel, a pivot member secured to the inner side of one end of the barrel, the other end of the barrel having an opening, and a stirrer comprising a bar pivotally connected with said member and normally extending parallel with the first mentioned end of the barrel, and a bar pivoted to the outer end of the first mentioned bar and extending longitudinally of the barrel adjacent the side wall thereof and with its free end bent inwardly and extending into said opening.

In testimony whereof I affix my signature.
FRED H. HAYWOOD.
